US00D787087S

(12) **United States Design Patent** (10) **Patent No.:** **US D787,087 S**
(45) **Date of Patent:** **** May 16, 2017**

(54) **HOUSING**

(71) Applicant: **HandyLab, Inc.**, Franklin Lakes, NJ (US)

(72) Inventors: **Patrick Duffy**, Whitmore Lake, MI (US); **Kerry Wilson**, Elkhart, IN (US); **Kalyan Handique**, Ypsilanti, MI (US); **Jeff Williams**, Chelsea, MI (US)

(73) Assignee: **HandyLab, Inc.**, Franklin Lakes, NJ (US)

(**) Term: **15 Years**

(21) Appl. No.: **29/554,066**

(22) Filed: **Feb. 8, 2016**

Related U.S. Application Data

(63) Continuation of application No. 13/474,980, filed on May 18, 2012, now abandoned, which is a continuation of application No. 12/178,584, filed on Jul. 23, 2008, now Pat. No. 8,182,763, which is a continuation-in-part of application No. 12/173,023, filed on Jul. 14, 2008, now Pat. No. 8,133,671, said application No. 12/178,584 is a continuation-in-part of application No. 12/218,498, filed on Jul. 14, 2008, now Pat. No. 9,186,677.

(57) **CLAIM**

The ornamental design for a housing, as shown and described.

DESCRIPTION

FIG. 1 is a front, top, and first side perspective view of a housing embodying our new design;

FIG. 2 is a front, top, and second side perspective view thereof;

FIG. 3 is first side view thereof;

FIG. 4 is a back perspective view thereof;

FIG. 5 is a front and top perspective view thereof; and,

FIG. 6 is a partial top perspective view thereof.

Broken lines are used to illustrate features of the housing which form no part of the claimed design. Broken lines showing a user's hands, sample tubes, and reagent holders are for the purpose of illustrating environment and form no part of the claimed design.

1 Claim, 6 Drawing Sheets
